(57) **CLAIM**

The ornamental design for an electrical junction box for
motor diagnosis, as shown and described.

DESCRIPTION

FIG. 1 is a front elevational view of an electrical junction
box for motor diagnosis showing our new design;
FIG. 2 is a rear elevational view thereof;
FIG. 3 is a top plan view thereof;
FIG. 4 is bottom plan view thereof;
FIG. 5 is a left side devotional view thereof;
FIG. 6 is a right side elevational view thereof; and,
FIG. 7 is a left side, front and top perspective view thereof.
